UNITED STATES PATENT OFFICE.

MATHEW KUKOVEC, OF CHICAGO, ILLINOIS.

DESIGN FOR A SHOE.

Application filed October 13, 1922. Serial No. 3,959. Term of patent 14 years.

To all whom it may concern:

Be it known that I, MATHEW KUKOVEC, a subject of the Kingdom of Yugoslavia, residing at Chicago, in the county of Cook and State of Illinois, have invented a new, original, and ornamental Design for Shoes, of which the following is a specification, reference being had to the accompanying drawing, forming part thereof.

The figure is an elevation showing my new ornamental design for a shoe.

I claim:

The ornamental design for a shoe as shown.

MATHEW KUKOVEC.
